(57) **CLAIM**

The ornamental design for a mesh for a lacrosse stick pocket as shown and described.

DESCRIPTION

FIG. 1 is a left side isometric view of a first embodiment of a mesh for a lacrosse stick pocket according to the invention; FIG. 2 is a right side isometric view thereof;

FIG. 3 is a front view thereof;

FIG. 4 is a rear view thereof;

FIG. 5 is a top view thereof;

FIG. 6 is a bottom view thereof; and

FIG. 7 is a right side view thereof, the left side view being a mirror image thereof;

FIG. 8 is a left side isometric view of a second embodiment of a mesh for a lacrosse stick pocket according to the invention;

FIG. 9 is a right side isometric view thereof;

FIG. 10 is a front view thereof;

FIG. 11 is a rear view thereof;

FIG. 12 is a top view thereof;

FIG. 13 is a bottom view thereof; and

FIG. 14 is a right side view thereof, the left side view being a mirror image thereof;

FIG. 15 is a left side isometric view of a third embodiment of a mesh for a lacrosse stick pocket according to the invention;

FIG. 16 is a right side isometric view thereof;

FIG. 17 is a front view thereof;

FIG. 18 is a rear view thereof;

FIG. 19 is a top view thereof;

FIG. 20 is a bottom view thereof; and

FIG. 21 is a right side view thereof, the left side view being a mirror image thereof;

FIG. 22 is a left side isometric view of a fourth embodiment of a mesh for a lacrosse stick pocket according to the invention;

FIG. 23 is a right side isometric view thereof;

FIG. 24 is a front view thereof;

FIG. 25 is a rear view thereof;

FIG. 26 is a top view thereof;

FIG. 27 is a bottom view thereof; and,

FIG. 28 is a right side view thereof, the left side view being a mirror image thereof.
